LINER HANGER

Charles K. Morgan, Los Angeles, Calif., assignor
to Lane-Wells Company, Los Angeles, Calif., a
corporation of Delaware

Application December 22, 1941, Serial No. 423,946

8 Claims. (Cl. 166—1)

My invention relates to liner hangers; that is, to devices for hanging or suspending perforated well liners or screens within the bottom portion of a well bore. Among the objects of my invention are:

First, to provide a liner hanger which is adapted to be used in those cases in which it is desired to fit a liner of maximum diameter in the well casing;

Second, to provide a liner hanger wherein fluid may be circulated between the liner hanger and surrounding casing either before or after the liner has been set;

Third, to provide a liner hanger and setting tool therefor which is adapted to insure setting of the liner hanger even though the liner should be "frozen" or stuck in the well bore in the course of washing or cleaning the well bore prior to setting the liner and liner hanger; and

Fourth, to provide a liner hanger and setting tool which incorporates a novel arrangement for holding the wedging slips, and for urging the slips into engagement with a surrounding casing.

With the above and other objects in view, as may appear hereinafter, reference is directed to the accompanying drawing, in which:

Figure 1 is a fragmentary elevational view of my liner hanger with the parts shown in the positions assumed when running into the well bore;

Figure 2 is a longitudinal half sectional view through 2—2 of Figure 1, with the parts shown in their initial position;

Figure 3 is a similar longitudinal sectional view with the parts shown in the positions assumed when the liner hanger is set or secured within a well casing;

Figure 4 is a fragmentary longitudinal sectional view similar to Figure 3, but taken through 4—4 of Figure 6, showing particularly the channel and rib connection between the traveler member and body of the liner hanger;

Figure 5 is a transverse sectional view through 5—5 of Figure 1; and

Figure 6 is another transverse sectional view through 6—6 of Figure 1.

My liner hanger comprises a tubular body 1 having a central portion which is externally cone-shaped, as indicated by 2. The conical portion 2 is adapted to receive a plurality of wedge-shaped slips 3 having on their exterior surfaces teeth or wickers for engagement with a surrounding casing. The slips are segmental in form, and centered with respect to each slip and extending axially upwardly therefrom are a series of dovetail channels 4 formed in the body 1. The slips

3 are provided with dovetail lugs 5 at their upper inner ends, which fit into the channels 4 so as to hold the slips against the body 1.

The lower or larger end of each slip initially rests against a shoulder 6 formed at the lower end of the conical portion 2. A tongue extends from the lower or thicker end of each slip 3. Each tongue 7 is provided with an inturned end 8 and fits within a slot 9 cut in the body 1. The extended ends of the tongues 7 are initially held against radial movement out of the slots 8 by retainers 10 which bridge the slots.

The lower portion of the body 1 below the conical portion 2 is counterbored, as indicated by 11, and the slots 9 extend through the walls of the body 1 into the counterbore. The counterbore receives a driving ring 12 having holes 13 which accommodate the inturned end 8 of the tongues 7. The driving ring 12 is urged upwardly within the body 1 by a coil spring 14 fitting in the counterbore 11. The lower end of the spring 14 bears against a shoulder formed by the upper inner end of an adaptor fitting 15 which is screw-threaded into the lower end of the body 1. The adaptor fitting is provided with suitable pipe threads at its lower end for connection to a liner A.

The liner hanger is initially connected to a setting tool which is suspended from a tubing string B. The setting tool includes a mandrel 16 which fits within the body 1 and is connected thereto by supporting threads 17 formed in the upper end of the body 1 and the mandrel 16. These threads are preferably left-hand threads so that they unscrew when the tubing is rotated in a direction tending to tighten the conventional couplings which join the sections comprising the tubing string.

The lower end of the mandrel 16 is provided with a traveler ring 18 which is connected with the mandrel by means of threads 19. The threads 19 are preferably right-hand threads; that is, opposite from the threads 17 and, also, are preferably double pitched, or double lead threads. The traveler ring 18 is provided with longitudinally extending ribs 20 which fit in longitudinally extending grooves 21 formed along the inner wall of the body 1. The grooves 21 are preferably equally spaced between the channels 4 and slots 9. The ribs 20 and grooves 21 coact to prevent rotation of the traveler ring when the mandrel 16 is rotated, and by reason of the double pitch right-hand threads 19, with each rotation of the mandrel the traveler ring is raised a distance of three threads. The ribs 20 initially par-

cially project below the grooves 21 into the counterbore 11 to engage the upper end of the driving ring 12, and hold the driving ring against upward movement; that is, retain the driving ring in the position shown in Figure 2.

The lower end of the mandrel 16 is provided with a suitable retainer ring 22 to prevent the traveler ring 18 from unscrewing, and the mandrel 16 is attached to a wash pipe C which extends downwardly within the liner A.

Operation of my liner hanger and setting tool is as follows: The liner hanger is run into the well with the parts in the positions shown in Figures 1 and 2; that is, the slips are in their retracted position and the traveler ring 18 is in its lower position, holding the spring 14 compressed. The liner is lowered until it engages the bottom of the well, and while the liner is held by such engagement the tubing string is rotated in a direction to unscrew the mandrel 16 from the body 1. After the mandrel is rotated a sufficient number of turns to release the slips, but before it is moved sufficiently to completely disengage from the body 1, the liner hanger is raised to the desired position in the well bore, preferably to a point in which the liner clears the bottom by a few feet, thereupon weight is applied to the liner to securely wedge the slips. When it is desired to free the setting tool from the liner it is merely necessary to continue rotation of the mandrel until the left-hand screw-thread connection 17 is separated.

It should be noted that in place of the traveler ring threads 19 the traveler ring may be merely journaled upon the mandrel, in which case it will raise only to the extent that the connection 17 is unscrewed, that is, assuming a single pitch thread connection 17 will advance upwardly one thread for each rotation and therefore require a greater amount of rotation to free the slips. If the traveler ring threads 19 are omitted it is, of course, obvious that the threaded connection 17 would be extended axially to insure continued engagement between the body and mandrel after the slips have been released. With the present arrangement, utilizing the dual thread connections 17 and 19, the amount of rotation of the mandrel in order to free the slips is reduced; therefore, simplifying this initial operation.

Various changes and alternate arrangements may be made within the scope of the appended claims, in which is is my intention to claim all novelty inherent in the invention.

Claim:

1. A liner hanger comprising: a body member having wedging faces and slots in said body member extending downwardly from said wedging faces; slips adapted to move along said wedging faces for engagement with a surrounding casing, and tongues on said slips extending through said slots to the interior of said body member; a coil spring lining the interior of said body member and operatively engageable with said tongues to urge said slips along said wedging faces; and a setting tool removably attachable to said body member and including a member operatively engageable with said tongues to restrain said slips in a retracted position against the tendency of said spring.

2. A liner hanger comprising: a body member having wedging faces and slots in said body member extending downwardly from said wedging faces; slips adapted to move along said wedging faces for engagement with a surrounding casing,

and tongues on said slips extending through said slots to the interior of said body member; an instrumentality within said body member engageable with said tongues and tending to urge said

- 5 slips along said wedging faces for engagement with said casing; and a setting tool including a mandrel having a readily separable screw-threaded connection with said body member, a traveler screw-threaded on said mandrel, and
10 key and slot means on said traveler and body member to restrain said traveler against rotation relative to said body member, said traveler engageable with said instrumentality to restrain said instrumentality and slips.
15 3. A liner hanger comprising: a body member having downwardly converging wedging faces, slots in said body member extending downwardly from the lower ends of said wedging faces and undercut grooves formed in said wedging faces
20 and continuing upwardly in said body member above said wedging faces; slips movable along said wedging faces, tongues on said slips fitly received in said slots and projecting into said body member, and lugs on said slips interlocking in said grooves to hold said slips against said wedging faces; a coil spring lining the interior of said body member and operatively engageable with said tongues to urge said slips along said wedging faces; and a setting tool including
25 30 a mandrel having a readily separable screw-threaded connection with said body member, a traveler screw-threaded on said mandrel, and key and slot means on said traveler and body member to restrain said traveler against rotation relative to said body member, said traveler engageable with said instrumentality to restrain said device and slips.

4. A liner hanger comprising: a body member having wedging faces and slots in said body member extending downwardly from said wedging faces; slips adapted to move along said wedging faces for engagement with a surrounding casing, and tongues on said slips extending through said slots to the interior of said body member; an instrumentality within said body member engageable with said tongues and tending to urge said slips along said wedging faces for engagement with said casing; and a setting tool, including means forming a separable connection with said body member and means for holding said slips in a retracted position.

5. A liner hanger comprising: a body member having downwardly converging faces, slots in said body member extending downwardly from the lower ends of said wedging faces and grooves formed in said wedging faces and continuing upwardly in said body member above said wedging faces; slips movable along said wedging faces, tongues on said slips fitly received in said slots and projecting into said body member, and lugs on said slips interlocking in said grooves to hold said slips against said wedging faces; and an instrumentality within said body member engageable with said tongues and tending to urge said slips along said wedging faces for engagement with said casing.

6. A liner hanger comprising: a body member having downwardly converging wedging faces, slots in said body member extending downwardly from the lower ends of said wedging faces and continuing upwardly in said body member above said wedging faces; slips movable along said wedging faces, tongues on said slips fitly received in said slots and projecting into said body mem-

ber, and lugs on said slips interlocking in said grooves to hold said slips against said wedging faces; an instrumentality within said body member engageable with said tongues and tending to urge said slips along said wedging faces for engagement with said casing; and a setting tool, including means forming a separable connection with said body member, and means for holding said slips in a retracted position.

7. A liner hanger comprising: a body member having downwardly converging wedging faces, slots in said body member extending downwardly from the lower ends of said wedging faces and undercut grooves formed in and continuing upwardly in said body member above said wedging faces; slips movable along said wedging faces, tongues on said slips fitly received in said slots and projecting into said body member, and lugs on said slips interlocking in said grooves to hold said slips against said wedging faces; and a coil spring lining the interior of said body member and operatively engageable with said tongues to urge said slips along said wedging faces.

8. A liner hanger comprising: a body member having downwardly converging wedging faces, slots in said body member extending downwardly from the lower ends of said wedging faces and undercut grooves formed in said wedging faces and continuing upwardly in said body member above said wedging faces; slips movable along said wedging faces, tongues on said slips fitly received in said slots and projecting into said body member, and lugs on said slips interlocking in said grooves to hold said slips against said wedging faces; a coil spring lining the interior of said body member and operatively engageable with said tongues to urge said slips along said wedging faces; and a setting tool removably attachable to said body member and including a member operatively engageable with said tongues to restrain said slips in a retracted position against the tendency of said spring.
